UNITED STATES PATENT OFFICE

132,312

DESIGN FOR A COMBINATION ASH TRAY AND CARD TRAY

Edward San Giovanni, New York, N. Y.

Application December 31, 1940, Serial No. 97,737

Term of patent 14 years

To all whom it may concern:

Be it known that I, Edward San Giovanni, a citizen of the United States of America and residing in the city and State of New York, have invented a new, original, and ornamental Design for a Combination Ash Tray and Card Tray, of which the following is a specification, reference being had to the accompanying drawing, forming part thereof.

I claim:

The ornamental design for a combination ash tray and card tray, as shown.

EDWARD SAN GIOVANNI.
